UNITED STATES PATENT OFFICE.

EDWIN I. GOLDING, OF NEW YORK, N. Y.

ADVERTISING MEANS.

Application filed January 27, 1921. Serial No. 440,469.

To all whom it may concern:

Be it known that I, EDWIN I. GOLDING, a citizen of the United States, and a resident of New York city, in the State of New York, have invented certain new and useful Improvements in Advertising Means, of which the following is a specification.

My present invention relates in general to the art of merchandizing manufactured products, and more particularly to the physical embodiments of certain desirable identifying characteristics imparted to a merchantable commodity such as piece-goods whereby a number of predetermined marked advantages and beneficial results are attained with certainty.

As is generally perceived, in the psychology of merchandizing there are a number of different forms and characters of selling appeals inherent in an article which renders it attractive to the purchaser. Some of these are materialistic or visible and others are intangible, for example, the nature and quality of the article, its texture, color, dress and appearance, its class, price and so forth.

One of the most important of the intangible elements and one that is most largely relied upon by the purchaser is however its source of origin, and for this the purchaser largely rests upon his confidence and credence in the seller and his belief in the standards zealously maintained by reputable and established merchants from time immemorial.

It is well known that a merchandizer, particularly a retailer or one who sells to the ultimate consumer will go to infinite pains and much expense in furtherance of his aim to associate his own name with the goods sold by him in the mind of the ultimate consumer, having in view a two-fold objective, to wit: primarily to cause the vendee to return to him for replenishment of supplies of the article sold, and secondarily to establish a general good will for his mercantile institution as the source of origin of desirable merchandize.

As will be apparent upon reflection such methods as properly may be utilized in directly or in indirectly impressing upon the vendee the name of the vendor who is known to him often personally, rather than that of some distant and unknown manufacturer,—in fact as many different methods, arrangements or procedures as may well be employed, are assured of not only passive

sympathy and favorable inclination but also of active support and co-operation of the ultimate merchandizer, and clearly leading to the eventual establishment of permanent commercial relations between him and those supplying merchandise characterized by the ability to impress the name of the vendor upon the vendee.

As my present invention adapted for the furtherance of the ends hereinabove suggested is peculiarly adapted and in fact primarily (though not exclusively) intended for use in connection with textile materials, specially in the piece, I shall proceed to illustrate and describe such invention as employed in connection with a bolt of cloth which may be of any desired character.

In the transmission of such merchandise as piece goods, whether through the mail, by common carrier, cartage, or otherwise, losses in transit by theft are of frequent occurrence, and similarly losses often occur through carelessness and through bursting of packages or the wrappers thereof, or mutilation or defacement of wrappers, rendering identification of the goods and delivery thereof either to consignor or consignee entirely impossible.

Furthermore, even if the goods themselves be not lost in transit, delays in delivery often occur owing to such destruction of the shipping tag or other lack thereof.

In the practice of my present invention, inasmuch as the name of the ultimate vendor, e. g., "John Doe" is impressed upon the selvage of the goods at repeated intervals, various desired results flow without special further action among which are:

(1) All whom it may concern or who may be interested know that said "John Doe" is responsible for the goods which thereby advertise him and not the producer;

(2) If the goods are lost or stolen and the selvage remains intact those into whose possession the goods may come are placed on notice that they are the property of said "John Doe" and are thereby offered the alternatives of restoring them to said "John Doe" or of voluntarily and wittingly becoming party to the unlawful conversion thereof;

(3) Should the goods come into the hands of a dishonest person who attempts to remove the indicia of the source of origin and of ownership by removal of the selvage, such mutilation of the goods will be ap-

parent upon even the most casual inspection and thereby put subsequent purchasers upon notice that the holder of the goods has questionable title.

- 5 By placing both the name and the address of the ultimate vendor, e. g. "John Doe, Jamestown, N. Y." upon the selvage of the goods, the further result is attained of being enabled to use this indicia impressed 10 upon the selvage as the final mailing, shipping, or delivery address of the one to whom the goods are addressed, consigned or directed.

In attaining these and other objects and 15 advantages, which will appear as this specification is read, or which will be pointed out hereinafter, I have provided an arrangement, one embodiment of which is illustrated in the accompanying drawings in 20 which;

Figure 1 illustrates a bolt of cloth embodying my invention; and in which only the name of the vendor appears upon the selvage;

- 25 Figure 2 shows a modified arrangement in which both the name and address of the vendor appear upon the selvage of the bolt of cloth;

Figure 3 shows a box or container to receive the bolt of cloth of Figure 2 and arranged to present to view through a face thereof the indicia on the selvage of the cloth of Figure 2; and

Figure 4 shows a wrapper of such dimensions as to expose to view the selvage of the cloth, with the indicia thereon.

The merchandizer who sells to the general public and who is commonly termed the retailer, and it is for his benefit that this invention has been particularly evolved, indulges in advertising with one or more of a number of ends in view among which are two of prime importance, namely; (1st) that of impressing his name and his establishment upon the mind of the purchaser or ultimate consumer with the end in view that such purchaser or ultimate consumer will instinctively turn to his store or establishment for general purchases along the 50 lines likely to be sold by such retailer; (2d) to establish such association between his name, store or establishment and certain goods, that his, the retailer's name will stand as the source of origin of the goods to the purchaser so that the purchaser will thus be advised that he can always look to said retailer as the guarantor of the goods, and as the man who stands in back of them, while the retailer will profit by the good 55 reputation which such goods establish with the purchasing public. An example of this character of advertising is found in the retailer using on his shirt a label in which such retailer's name or trade mark or both 60 alone appear. The name of this retailer

therefore becomes in effect the guarantee for the goods.

My present invention is directed primarily to the second of these ends, although as will be obvious, its beneficial results will also 70 extend to the first.

In Figure 1 in which I have illustrated my invention as associated with and embodied in the bolt of cloth 10, the name of the merchant who sells to the ultimate consumer, and who will hereafter be referred to as the retailer, appears on the selvage 11. This name indicated at 12 is given as "John Doe" for purposes of illustration. This name is repeated at frequent 80 intervals along either one or both selvages, as desired, and preferably at such intervals, as to cause the name to appear upon the smallest piece of goods sold commercially. The ultimate consumer in purchasing a piece 85 of material having the name of the retailer on the selvage thereon at the intervals preferred above, will therefore have in front of him impressed upon the goods, the name of the retailer from whom he purchased the 90 goods, which will obviously add an element of confidence to his purchase, not present before, particularly when he has in tangible form at all times the name of the retailer from whom the goods were purchased. At 95 the same time, as is obvious, the good reputation which the goods attain, will result in repeated purchases from the one whose name appears on the selvage. In other words the retailer's own name thus appears 100 as the guarantor for the goods.

My invention presents the added advantages that the shipment or delivery of the goods to the retailer can be started with a full assurance that the goods cannot become 105 lost in transit due to loss of the name of the consignee. The name of the retailer irremovably associated therewith is that of the consignee. Furthermore the theft of the goods will always present to the one guilty 110 of such theft the embarrassment and difficulty of having the rightful owner's name on the selvage, which will at once call for an explanation when in the hands of one other than the one so named, as will also the 115 absence of the selvage, in case the selvage is cut off to hide the theft.

Where a bolt of cloth is to be delivered or shipped in wrapped condition, I have devised the box or wrapper indicated generally at 15 in Figure 2, the box or wrapper 15 being provided with the opening or window 16 positioned so as to register with and expose to view, the name of the retailer to whom the goods are to be delivered. This window may, if desired, be closed by a transparent material. Where such shipment or delivery is to be made at a distance, it may be found desirable for the purpose of securing this added advantage to place 120

upon the selvage both the name and the address of the retailer e. g. "John Doe—New York, N. Y.", as indicated at 19 in Figure 2. The indicia on the selvage are repeated 5 as often as thought advisable, and preferably are so arranged that the complete indicia will at all times register with the opening 16 in the box or container 15.

Where on the other hand the bolt is delivered by messenger to a retailer close by, the completely enclosing box or wrapper may not be necessary. For this purpose I have illustrated in Figure 4 the bolt 10, having the wrapper paper 18 thereabout of such a 15 width as not to cover either or both of the selvages, thus exposing the desired indicia to view, which thus serve the added function of delivery directions.

Having thus described my invention and 20 illustrated its use, what I claim as new and desire to secure by Letters Patent is:

1. In combination with an article of merchandise of a textile character having a selvage and intended to be subdivided into 25 smaller portions for purposes of sale, and having indicia irremovably associated with said selvage and repeated at intervals, said indica being of a character to

indicate the one to whom the goods are to be delivered for purposes of sale, and when 30 so delivered to thereafter indicate to purchasers of all or of parts thereof, the one from whom the merchandise was purchased, of a receptacle or retainer for said merchandise having a window or opening arranged to expose portion of said selvage to view the opening and the indicia being so proportioned and positioned relatively to each other that a complete indicia will at all 35 times be in registry with the opening. 40

2. In combination with an article of merchandise of a textile character and intended to be subdivided into smaller portions for purposes of sale and having indicia thereon irremovably associated therewith and repeated at predetermined intervals, said indicia being of a character to indicate ownership, of a container having an opening therein, the opening and the indicia being so proportioned and positioned relatively to 45 each other, so that a complete indicia will at all times be in registry with the opening. 50

In testimony whereof I have hereunto signed my name.

EDWIN I. GOLDING.
